COMBINED SPRINKLING METER AND SHUTOFF VALVE

E. Burton Benjamin, Highland Park, Ill., assignor to
Ansan Tool and Manufacturing Company, Inc., Chi-
cago, Ill., a corporation of Illinois

Filed Feb. 1, 1968, Ser. No. 10,411

Term of patent 14 years

(Cl. D23—38)

FIG. 1 is a perspective view of a combined sprinkling meter and shutoff valve showing my new design;

FIG. 2 is a side elevational view of the left side of FIG. 1;

FIG. 3 is a top plan view thereof;

FIG. 4 is a rear elevational view thereof;

FIG. 5 is a bottom plan view thereof; and

FIG. 6 is a fragmentary sectional view on an enlarged scale, taken along the line 6-6 of FIG. 4, looking in the direction of the arrows.

I claim:

The ornamental design for a combined sprinkling meter and shutoff valve, substantially as shown.
